UNITED STATES PATENT OFFICE.

JACOB WELTY AND ARTHUR A. LEACH, OF HAYESVILLE, OHIO, ASSIGNORS
OF ONE-THIRD TO HEZEKIAH BUTCHER, OF SAME PLACE.

CLOVER-SEED RECLEANER.

SPECIFICATION forming part of Letters Patent No. 447,801, dated March 10, 1891.

Application filed September 5, 1890. Serial No. 363,988. (No model.)

To all whom it may concern:

Be it known that we, JACOB WELTY and ARTHUR A. LEACH, citizens of the United States, residing at Hayesville, in the county 5 of Ashland and State of Ohio, have invented a new and useful Clover-Seed Recleaner, of which the following is a specification.

This invention relates to clover-hullers, and it has especial reference to that part of clover-hulling machines which is known as the "recleaner," and which serves more especially to 10 separate the pure clover-seed from the lighter and defective qualities and from the seeds of weeds which are apt to become mixed there- 15 with.

The object of our present invention is to construct a machine by means of which the process of recleaning may be carried out easily and efficiently, and which shall be adapted to 20 operate equally well upon dry and damp seeds.

With these ends in view the invention consists in the improved construction, arrangement, and combination of parts, which will be hereinafter fully described, and particularly 25 pointed out in the claims.

In the drawings hereto annexed, Figure 1 is a longitudinal vertical sectional view of our improved clover-seed recleaner as adapted especially to operate upon dry seed. Fig. 2 is a 30 longitudinal sectional view illustrating the modification of the invention, whereby it is adapted to operate more especially upon damp seed. Fig. 3 is a transverse section taken on line 3 3 in Fig. 1. Fig. 4 is a transverse section taken on the line 4 4 in Fig. 2.

Like numerals of reference indicate like parts in all the figures of the drawings.

In the casing 1, which is of ordinary construction, is located the shoe 2, which is adapted 40 to receive a vibrating motion from the shaft 3 of the fan 4, which is journaled in the usual manner in the front part of the casing. A rifled screen 5 is arranged in an inclined position in the bottom of the shoe and extends 45 into the escape-spout 6. The upper part of the shoe above the fan has the rearwardly-inclined wind-board 7, and the sides of the shoe are provided with interiorly-located longitudinal cleats 8, the purposes of which will 50 hereinafter be made apparent. An inlet-spout

or hopper is suitably arranged in the casing above the wind-board 7.

10 designates a supplemental shoe, which is composed of the side pieces 11, connected at their upper edges by the screen 12. The lower edges of the side pieces 11 are connected by the screens 13 and 14, the latter of which is inclined in an upward and forward direction and under which is arranged an inclined plate or deflector 15, the lower edge of which communicates with a transverse spout 16.

When dry seeds are fed into the casing through the spout or hopper 9, they drop upon the inclined wind-board 7 and pass from thence onto the screen 12. The light and 65 worthless seeds pass through the screen 14 onto the inclined plate 15 and from thence into the transverse trough or chute 16, through which they are conveyed to one side of the casing. Light chaff and hulls are blown out 70 through the tail end of the casing and the good seeds drop onto the rifled screen 5, passing over the succession of steps formed upon the latter and being continually exposed to the blast from the fan until the perfect seeds 75 finally escape through the spout 6.

By the modification of our invention illustrated in Fig. 2 the supplemental shoe 10 and its attachments will be dispensed with and a shoe 18, having a series of steps 19, 20, and 21, 80 each covered with wire-netting of increasing coarseness, substituted. The bottom of the shoe has a screen 22, over which is arranged a longitudinally-sliding plate or deflector 23, having a handle 24, which extends to the rear 85 end of the casing of the machine, so that it may be readily manipulated or adjusted to any desired position. The front end of the shoe 18 normally rests upon the cleats 8, and guide-cleats 25 are provided to guide the deflector 23 in the said shoe. The said cleats 8 are not used except in connection with the shoe 18 to support the front end of the latter; but they are for convenience left as permanent fixtures in the permanent shoe 2. When the 90 shoe 18 is used, a top screen 26 is interposed between it and the supply-spout 9. The operation of this modification of our invention will be readily understood. The deflector or plate 23 may be readily adjusted so as to dis- 100

charge the seeds more or less to the rear, thus increasing or diminishing the screening capacity of the screens 22 and 5 to suit the more or less damp condition of the seeds.

5 It is obvious that in all cases the several screens that are employed are to be of different mesh. The grades may be determined upon by experiment and practice.

Having thus described our invention, what we claim is—

10 1. In a clover-seed recleaner, the combination, with the casing having the inlet 9 and outlet 6, of the vibratory shoe 2, having an inclined riffled-bottom screen, and an auxiliary shoe mounted detachably in the said main shoe and having suitably-arranged screens, substantially as and for the purpose set forth.

15 2. In a clover-seed recleaner, the combination, with the casing having the fan, of the vibratory shoe 2, mounted in said casing and having the wind-board or deflector 7 and the inclined riffled-bottom screen 5, and an auxiliary shoe mounted detachably in said main shoe, abutting against the wind-board, and

having suitably-arranged screens, substantially as and for the purpose set forth. 25

3. In a clover-seed recleaner, the combination, with the casing having the fan, the inlet 9, and outlet 4, of the vibratory shoe mounted in said casing and having the inclined riffled-bottom screen extending into the outlet-chute and the wind-board 7, and an auxiliary shoe mounted detachably in the said main shoe and having a bottom screen 22, a series of top screens 19, 20, and 21, and a longitudinally-30 movable plate or deflector 23, arranged between the top and bottom screens and having a handle extending through the rear end of the casing, substantially as set forth. 35

In testimony that we claim the foregoing as 40 our own we have hereto affixed our signatures in presence of two witnesses.

JACOB WELTY.
ARTHUR A. LEACH.
